UNITED STATES PATENT OFFICE.

CARL A. BAUMLER, OF ST. LUCAS, IOWA.

DESIGN FOR A TOOL FOR APPLYING AND REMOVING LOCK-NUTS.

52,262.

Specification for Design.

Patented Aug. 20, 1918.

Application filed May 20, 1916. Serial No. 98,956. Term of patent 3½ years.

To all whom it may concern:

Be it known that I, CARL A. BAUMLER, a citizen of the United States, residing at St. Lucas, in the county of Fayette and State of Iowa, have invented a new, original, and ornamental Design for a Tool for applying and removing lock-nuts, of which the following is a specification, reference being had to the accompanying drawing, forming part thereof.

Figure 1 is a side view,
Fig. 2 is an edge elevation,
Fig. 3 is an opposite edge elevation.

I claim:

The ornamental design for a tool for applying and removing lock nuts, as shown.

CARL A. BAUMLER.
